REFRIGERATOR CAR CONSTRUCTION

Charles D. Bonsall, Pittsburgh, Pa., assignor, by
mesne assignments, to Standard Railway Re-
frigerator Company, a corporation of Delaware

Application August 21, 1939, Serial No. 291,134

8 Claims. (Cl. 62—17)

This invention relates to refrigerator cars used to transport perishable commodities at a predetermined temperature. The essential features of a refrigerator car are an insulated body to prevent or retard ingress of heat during warm weather and egress of heat during cold weather and a cooling means and a heating means to be used during warm and cold weather respectively.

This invention applies particularly to cars in which the cooling means, preferably containers for water ice, eutectic ice, brine or dry ice, are disposed immediately below the roof of the car. The lading is supported in spaced relation to the floor by a foraminous rack. Flues, preferably associated with the side walls of the car, communicate between the cooling means and the space under the floor rack to provide a path for the circulation of air. The path is from the cooling means downwardly through the aforementioned flues, through the space under the floor rack, upwardly through the lading compartment thereby cooling the lading, and finally to the cooling means from where the cycle is repeated.

The refrigerant containers in a car of this design may be of several types. The containers may be composed entirely of wire mesh or other foraminous material, in which case the liquid resulting from melting of the refrigerant would pass immediately through the container and would have to be disposed of at once. The lower part of a container may be solid with the upper part formed of a foraminous material, in which case a portion of the melted refrigerant would be retained in the lower solid part, while the remaining liquid would overflow the solid part due to an accumulation of liquid or due to splashing through the foraminous part during movements of the car. Another type of container may be substantially imperforate except for a relatively few ventilating apertures adjacent the top thereof, in which case a certain amount of liquid would splash through the apertures during movements of the car. In another case the container may be entirely imperforate without provision for overflow of liquid, but the cold surface of the container would condense a certain amount of moisture which would have to be disposed of.

Recent experiments in the transportation and storage of perishable commodities indicate that several factors are important in the preservation of the commodity. Two of the most important are humidity and temperature. A low temperature is not sufficient for some products, but must

be accompanied by a high humidity to prevent wilting of the product.

As has been heretofore described, air circulating within the car is cooled by contact with the refrigerant containers. Means are provided in a car of this type for the cooled air and the liquid overflowing to the container, as well as condense therefrom, through the same flue on the way of the lower part of the car. In this way the air is further cooled by contact with the cold liquid and also humidified by such contact.

It is an object of the invention to provide a trough in such a position that it catches the liquid flowing from the container and also to position the trough so that the air circulating within the car can come in contact with the liquid contained therein, thereby still further cooling and humidifying the circulating air. A further object of the invention is to temporarily retain at least a portion of the liquid in the trough until substantially all of the refrigerating effect is obtained therefrom.

Another object of the invention is to provide means for disposing of the liquid from refrigerant containers without wetting the lading. Railway cars are subject to violent movements so that a liquid is liable to be splashed considerable distances if preventive means are not provided.

A still further object of the invention is to provide means within the trough to prevent liquid retained therein surging from end to end of the car. It is obvious that circulating air cannot be uniformly cooled and humidified throughout the car if all of the liquid is at one end of the trough. Furthermore, to prevent liquid surging lengthwise of the car is to protect the lading from being dampened by the splashing of the liquid.

Another object of the invention is to retain the liquid at substantially equal levels throughout the length of the trough. Under certain conditions the refrigerant may melt faster in one end of the car than in the other end, therefore, a great amount of liquid would accumulate at one end if equalizing means are not provided.

Another object of the invention is to prolong the life of the car floor. Salt is commonly mixed with the refrigerant in the containers to provide a lower temperature and salt brine, as well as small particles of salt, often descend through the side wall flues. By trapping the brine, and particularly the salt particles in the trough, the corrosive action thereof upon the main floor is greatly retarded with a consequent increase in the life thereof. The trough can be made of a

thicker or alloyed material to withstand the corrosion and the floor of less expensive, less resili-ent material.

A further object of the invention is to provide a sloping surface below the flue upon which surface the liquid falling vertically through the side wall flue may fall and be sprayed or atomized. Air flowing through the spray created thereby would be cooled and humidified by contact therewith.

Other objects and advantages of my invention will be apparent from the following detailed description by referring to the accompanying drawings.

In the drawings:

Fig. 1 is a perspective view of a portion of a refrigerator car embodying my invention.

Fig. 2 is a transverse section of the car shown in Fig. 1 including arrows to show the direction of flow of air and liquid.

Fig. 3 is a plan section of line 3—3 of Fig. 2.

Figs. 4 and 5 show modified forms of my invention.

Fig. 6 is a section to a larger scale showing the details of the drain trap as indicated by the line 6—6 of Fig. 3.

Figs. 7 and 8 show modified forms of troughs.

The general parts of the refrigerator car shown are insulated roof 2; side walls 3; floor 4; hatch 5; refrigerant container 6; side wall flue 7; foraminous floor rack 8 and space 9 between the rack 8 and floor 4. A refrigerant container 6 is positioned directly below the roof 2 and adjacent the side wall 3. A drip pan 12 is provided below the container 6 and a partition 14 is secured in an upstanding position at the edge of the drip pan 12. The drip pan 12 and partition 14 cooperate with the roof 2 and side wall 3 to form an enclosing structure 11 around the container 6, an air inlet opening 15 being provided by spacing the partition 14 from the roof 2. An air discharge opening 17 which leads to the flue 7 is formed by spacing the drip pan 12 from the wall 3.

Air circulation is as follows: Air in the lading compartment 18 is warmed by contact with the lading and rises to enter the enclosing structure 11 through the air inlet opening 15. The air is cooled by contact with the refrigerant container 6 and falls by reason of its greater density through the discharge opening 17 and flue 7 to the space 9 whence it rises through the rack 8 to the lading compartment 18. Cars of this type usually have a row of refrigerant containers near each wall and directly below the roof so that air flowing from the lading compartment flows between the containers disposed on opposite sides of the car.

The form of refrigerant container 6 shown in the drawings is one in which the bottom 20 and the lower parts of the walls 21 are imperforate. The upper parts of some of the walls are provided with apertures 24 through which ventilating and refrigerating air may circulate and through which a certain amount of liquid will splash from the container 6. It is to be understood that my invention is not to be limited to a refrigerator car having a container of this type, but that it also pertains to completely foraminous or completely imperforate containers.

The arrows in Fig. 2 show the path of the circulating air and liquid; the dotted arrows 27 indicating water and the solid arrows 28 air. Some of the liquid in the container 6 flows through certain apertures 24 in the container

wall 22, through the duct 29 below the container 6 and through the side wall flue 7, therefrom falling upon the sloping surface 31 from which it is deflected into the trough 32. Some liquid may also flow through the apertures 24 in the container wall 25, therefrom flowing through the flue 7 to the sloping surface 31 and trough 32. As shown most clearly in Figs. 1 and 3, the flue 7 and trough 32 are substantially continuous longitudinally of the car and extend from end to end thereof. Air circulating within the car rises through the opening 15, part of the air flowing into the apertures 24 and through the container and part under the container 6 through the duct 29. The circulating air then flows downwardly through the side wall flue 7 and trough 32. Circulating air in passing adjacent the trough 32 is refrigerated and humidified by contact with the cold liquid in the trough and with the spray created by the liquid falling upon the sloping surface 31. The air then flows through the space 9 under the floor rack 8 and upwardly toward the roof of the car, repeating the cycle just described.

In order to prevent liquid in the trough 32 surging from end to end of the car during service movements thereof, spaced apart partitions or baffles 35 are provided in the trough 32. It is preferable to provide small openings in the baffles 35 so that the liquid retained in the several portions of the trough 32 included between the baffles 35 may find a common level. The apertures in the baffles may be holes 36 spaced above the bottom of the trough 32, as shown in Fig. 2, or holes 37 adjacent the bottom of the trough 32, as shown in Fig. 4. The entire lower edge 39 of the baffle 40 may be spaced a small distance above the bottom of the trough, as shown in Fig. 5.

There is a tendency during movements of the car for liquid to splash from the trough 32 toward the lading compartment 18. Some means, such as the inclined lip 43 shown in Fig. 4, or the horizontal lip 44, shown in Fig. 5, may be provided to prevent splashing of the liquid. A lip 45, as shown in Fig. 5, may also be provided adjacent the side wall 3 to prevent liquid splashing from the trough 32 being deflected by the side wall 3 into the lading compartment 18. The lips 43, 44 and 45 may be formed by overlapping the margins of the trough 32 with the margins of the floor sheet 46 or side wall flue sheet 47; the margins preferably being welded together.

For certain types of service, top ice, which is ice placed on top of the lading in direct contact therewith, is used. When the top ice melts, the liquid formed thereby seeps downwardly to the floor 4 of the car and should, if possible, drain to the trough 32. The lip 44 shown in Fig. 5 would permit drainage of such liquid into the trough 32, whereas if the lip 43 shown in Fig. 4 is used, it would be necessary to provide small apertures at intervals in the lip 43 so that the melted top ice could be drained to the trough 32.

It is desirable that at least a portion of the melted refrigerant should be retained in the trough 32 a sufficient length of time for the circulating air to obtain the greatest possible refrigeration and humidification therefrom. For this purpose, a trap 50 shown in Figs. 3 and 6 may be provided. The trap 50 consists of a substantially vertical pipe 51 projecting through the bottom 52 of the trough 32 and leading to the exterior of the car, the top of said pipe being disposed a substantial distance above the bottom of the trough 32 so that the liquid within the trough has to be of a height reaching to the top of the

pipe 51 before it can escape. A cap 53 is preferably provided above the pipe with its lip 55 at a lower level than the top of the pipe 51 to prevent air entering the car through the pipe 51. The cap 53 is preferably hinged at 56 to facilitate cleaning of the trap 50.

Fig. 7 shows a modified construction in which the upper surface of the floor 4 consists of a layer of wooden flooring 60. The trough 32 comprises a channel shaped member 61 having the web 62 thereof preferably resting upon the wooden flooring 60.

In the modification shown in Fig. 8, the trough 32 has a downwardly and outwardly inclined bottom 64 so that liquid or solid particles descending through the flue 7 splash away from instead of toward the lading compartment 18.

The term "refrigerator car" used herein is not intended to limit the invention to a structure in which the car body is permanently attached to the trucks. The invention also applies to containers and other similar structures adapted to be temporarily or permanently mounted upon railway cars or highway trucks.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a refrigerator car body, refrigerating means in the upper part of the car body, a longitudinally extending flue associated with a wall of the car body arranged to conduct to the lower part thereof cold liquid from said means and air refrigerated by said means, a longitudinally extending trough associated with the floor of the car body, and an inclined surface below said flue to direct said air and said liquid into said trough thereby further cooling said air.

2. In a refrigerator car body, refrigerating means in the upper part of the car body, a longitudinally extending flue associated with a wall of the car body arranged to conduct to the lower part thereof cold liquid from said means and air refrigerated by said means, a longitudinally extending trough associated with the floor of the car body arranged to receive said liquid from said flue and positioned so that said air passes over the liquid contained therein thereby further cooling said air, and means to prevent splashing of liquid from said trough to the lading compartment of the car body.

3. In a refrigerator car body having a wall and a floor, refrigerating means in the upper part of the car body, a longitudinally extending flue associated with said wall and arranged to conduct to the lower part thereof cold liquid from

said means and air refrigerated by said means, a longitudinally extending trough associated with said floor arranged to receive said liquid from said flue and positioned so that air flowing from said flue flows over the liquid in said trough, and spaced apart baffles in said trough to retard surging of liquid from end to end thereof.

4. In a refrigerator car body having a wall and a floor, refrigerating means in the upper part of the car body, a longitudinally extending flue associated with said wall and arranged to conduct to the lower part thereof cold liquid from said means and air refrigerated by said means, a longitudinally extending trough associated with said floor arranged to receive said liquid from said flue and positioned so that air flowing from said flue flows over the liquid in said trough, and a covering for said floor, the margin of said covering adjacent said trough being secured to a wall of said trough in overlapping relation therewith, the overlapping portion overhanging said trough to prevent splashing of liquid therefrom.

5. A structure as defined in claim 3 wherein said baffles have apertures therein to retain liquid at substantially the same level throughout said trough.

6. A structure as defined in claim 3 wherein said baffles are spaced from the bottom of the trough to retain liquid at substantially the same level throughout said trough.

7. In a refrigerator car having a wall and a floor, said wall comprising a sheet member, said sheet member having formed therein an outwardly projecting panel connected to a marginal part of said member by an inclined web, and a lining disposed in flatwise relation to said member to form a flue between said lining and said panel, refrigerating means in the upper part of the car arranged to discharge cold liquid and cold air into said flue, and a trough associated with said floor, said web being disposed at least partially below said flue and arranged to direct said liquid into said trough and to direct said air into contact with the liquid in said trough.

8. In a refrigerator car having a wall and a floor, a foraminous rack forming a space between the rack and said floor, said wall comprising in part a sheet member, said sheet member having formed therein an outwardly offset part having an inclined web associated therewith, a lining disposed in flatwise relation to said member to form a flue between the lining and said offset part, refrigerating means in the upper part of the car arranged to discharge cold liquid and cold air into said flue, and a trough associated with said floor, said web being arranged to direct said liquid into said trough and to direct said air into said space.

CHARLES D. BONSALL.
